FELIPE MEJIA BORJA, OF NEW YORK, N. Y.

SWINGING CLOTHES-LINE SUPPORT.

1,149,894.

Specification of Letters Patent. Patented Aug. 10, 1915.

Application filed May 21, 1914. Serial No. 840,024.

To all whom it may concern:

Be it known that I, FELIPE MEJIA BORJA, a citizen of the Republic of Mexico, and a resident of the city of New York, borough 5 of Manhattan, county and State of New York, have invented a new and Improved Swinging Clothes-Line Support, of which the following is a full, clear, and exact description.

- 10 This invention relates to improvements in clothes line supports, and particularly to supports which may be connected with a window frame so as to swing interiorly and outwardly, as desired.
- 15 The object in view is to provide a swinging support for clothes lines which may be readily moved into the room and moved out of the room at any time, and also readily adjusted for tightening the lines carrying 20 the clothes.

A further object of the invention is to provide an improved swinging clothes line support which is arranged with folding parts whereby the support may be folded into a 25 small space when it is desired to store the same or transfer the same.

In carrying out the objects of the invention a suitable bracket is connected with the side of the window or other convenient 30 point. To this bracket is pivotally connected a swinging arm which is provided with a double hinge intermediate the ends and a sleeve for holding the hinge against independent movement while the arm is in use. 35 Connected with the outer end of this arm is a second arm or projection which carries a pulley. Passing through this pulley and through a second pulley supported by a cable is the clothes line which may be readily tightened or loosened as desired upon elevating or depressing the pulley supported by the cable just mentioned. The arm may 40 be readily swung into the room whenever desired for applying clothes to the line, and may be readily swung out of the room when the support is not desired and the line is 45 not in use.

In the accompanying drawings, Figure 1 50 is a fragmentary horizontal section through a window, the same showing a swinging clothes line support embodying the invention in position for use; Fig. 2 is a horizontal vertical section through Fig. 1 approximately on line 2-2; Fig. 3 is an enlarged detailed fragmentary view showing part 55 of the supporting arm and disclosing the hinge intermediate the ends and a swinging journal or support; Fig. 4 is a detailed fragmentary top plan view of the supporting 60 plate for the arm shown in Fig. 3; Fig. 5 is a plan view of a supporting bracket embodying certain features of the invention.

Referring to the accompanying drawings by numeral, 1 indicates a wall of any desired kind and 2 a window frame of any desired kind. Applied to part of the window frame 2 is a bracket 3, which bracket is provided with a screw 4 extending into the wall 1 and a threaded extension 5 extending through part of the frame for receiving a clamping nut 6, whereby the bracket is properly held in place. Bracket 3 is provided with an upstanding portion 7 for receiving a second bracket or supporting plate 8, which supporting plate is provided with a threaded extension projecting through upstanding member 7 for receiving a clamping nut 9. Plate 8 is provided with a plurality of apertures 10 as shown in Figs. 3 and 4, which apertures are designed to receive at different times the locking pin 11 pressed by spring 12 and retracted by a hand operated rod or member 13. The pin 11 and spring 12 together with member 13 are carried by the outer section 14 of arm 15. A suitable bore is of course provided for the pin 11 so that the same may be raised at any time, thus allowing the arm 15 to swing from one position to the other and then be locked in its adjusted position by pin 11 entering one of the apertures 10. Plate 8 in addition to the aperture 10 is provided with a journal member 16 carrying a retaining screw 17, this journal member accommodating the section 14 of arm 15, as clearly shown in Fig. 3. The sections 14 and 14' of arm 15 are connected together by a double hinge 18 whereby these sections 19 may be folded together. When it is desired to cause the sections 14 and 14' to remain in alinement, as shown in Fig. 1, a sleeve 19 is moved over the hinge 18 and thereby stiffens or prevents the movement 105 of one section independent of the other. From Fig. 3 it will be observed that the sleeve 19 is provided with slots 20, which slots accommodate the heads 21 and 22 of a retaining member 23, which retaining member 110 may be operated from either side of the arm 15. When the arm is to be folded

the sleeve 19 is moved to the position shown in Fig. 3 and then section 14' may be moved over against section 14 and either head 21 or head 22 passed through slot 24 according to the direction in which the sections are folded.

After the arm 15 has been mounted as shown in Figs. 1, 2 and 3, a clothes line 25 is passed through pulleys 26 and 27. Pulley 26 is connected to an extension 28 by any suitable means, as for instance hook 29, extension 28 being connected with the section 14' of arm 15 by any suitable means, as for instance by being extended therethrough and clamped thereto by a nut 30. Pulley 27 is supported by a cable 31 passed over pulley 32, which pulley is in turn supported by hook 33 connected to bracket 34 secured to the wall or frame by screw 35, and by having part of the bracket extending through the walls of the frame and clamped thereto by a suitable nut 36. The cable 31 in passing through pulley 32 extends downwardly, and is wrapped around the upstanding member 7 on bracket 3 where it may be tied if desired, and thus positively support or hold in an elevated position the pulley 27.

When it is desired to use the device the arm 15 may be swung into the room to any desired extent and locked in the position in which it is moved by pin 11 engaging one of the apertures 10. The arm may be left within the room during the time that the clothes are drying or moved to an outer position, as desired. When moved to an outer position the line 25 may be tightened by raising pulley 27. When there is no further use for the line pin 11 is raised and arm 15 is swung to an outer position where it is locked by merely releasing pin 11, which will automatically move into one of the apertures 10 under the action of spring 12.

What I claim is—

1. In a clothes line support of the character described, a swinging arm, means for connecting the same to a window so that the arm may swing in and out of the window, means for supporting a clothes line on said arm, means for bringing said clothes line under tension, said arm being formed into an outer and an inner section, means for pivotally connecting said sections together so that one section may be folded against the other, a notched sleeve arranged on one of said sections and adapted to slide over the other section, said outer section being formed with an aperture, and a rotatable locking member arranged on said inner sec-

tion formed with enlarged ends, said enlarged ends fitting into said notches of the 60 sliding sleeve when the sleeve is moved away from said pivotal means, said locking member being formed with a head for locking said sections together when in a folded position, said head being adapted to be passed 65 through said aperture in said outer section, and to be caused to straddle said aperture when the sections are in a folded position.

2. In a clothes line support of the character described, a swinging arm formed with 70 an inner and an outer section, said outer section being formed with an aperture, a hinge member arranged between said sections for pivoting the sections together in such a manner that the sections may be folded 75 against each other, a sleeve arranged to slide over said hinge member and engage the ends of both of said sections whereby said sections are held in rigid alinement, said sleeve being formed with a pair of notches and a 80 rotatable locking member arranged on said inner section, said locking member being arranged in such a position as to be located in said notches when said sleeve is positioned entirely on said inner section, said 85 locking member being formed with an elongated head adapted to pass through said aperture in the outer section when in one position and adapted to span said aperture when in another position, whereby the sections of said arm may be folded and locked 90 in a folded position.

3. In a clothes line support of the character described, a supporting bracket, an arm pivotally mounted on said bracket, means 95 for locking said arm in various positions, said arm being divided into sections, a double hinge structure connecting said sections whereby the sections may be folded together, a telescoping sleeve surrounding one of said 100 sections and being adapted to telescope over the other section for engaging both sections adjacent said hinge and thus holding the sections rigidly in alinement, means for supporting a pulley on the outer section, a 105 clothes line arranged in said pulley, and manually operated means engaging said clothes line for bringing the same under tension.

In testimony whereof I have signed my 110 name to this specification in the presence of two subscribing witnesses.

FELIPE MEJIA BORJA.
